UNITED STATES PATENT OFFICE.

STEPHEN R. PARKHURST, OF BLOOMFIELD, NEW JERSEY, ASSIGNOR TO
EMILY R. PARKHURST, OF THE SAME PLACE.

IMPROVEMENT IN MACHINES FOR PICKING AND CLEANING COTTON AND WOOL.

Specification forming part of Letters Patent No. **56,675**, dated July 24, 1866.

To all whom it may concern:

Be it known that I, STEPHEN R. PARKHURST, of Bloomfield, in the county of Essex and State of New Jersey, have invented, made, and applied to use a certain new and useful Improvement in Cotton and Wool Picking Machines; and I do hereby declare the following to be a full, clear, and exact description of the same, reference being had to the annexed drawings, making part of this specification, wherein—

Figure 1 is a vertical section of my wool-picking machine. Fig. 2 is a plan of the oiling and condensing apparatus. Fig. 3 is a plan of one of the bars of the picker-cylinder. Fig. 4 is a section and partial elevation of one of the feeding-rollers.

Similar marks of reference denote the same parts.

In the first picking of wool it is usual to throw off the wool into a room by a brush-blower, while the burrs and foreign substances are received into a box. After this the wool is taken to the first breaker and there weighed out upon the feeding-apron, thus requiring an attendant and involving also loss of time in gathering up wool from the picker.

The nature of my said invention consists in a picker for wool and other fiber peculiarly constructed and arranged so as to loosen and open the fiber and remove foreign substances, and in combination therewith I employ a condensing apparatus that receives the wool or other fiber from the picker and discharges it in the form of a sliver or roving into a can, or it may be wound upon a spool or roller and at the same time oiled, so that the subsequent handling operations and weighing are rendered unnecessary, said sliver being fed directly into the carding-machines. This condensing apparatus consists of a pair of perforated rollers or drums that are revolved by competent mechanism, and receive upon their surface the said fiber as thrown off from the picker.

In the drawings, *a* is the feeding-belt, of usual character. *b* and *c* are feed-rollers. These are made of a series of teeth cut out of sheet metal, such as steel. The rollers themselves are composed of metal with a series of grooves turned in their surface of a width to receive

the bases of the sheet-metal teeth, and these teeth are held in place by upsetting the metal of the ribs on the surface of said rollers, so as to clinch over and hold in the bases of the sheet-metal teeth, as seen in Figs. 1 and 4.

The picker-cylinder *d* is made of a series of grooved bars, *1 1*, set on heads, said grooved bars *1 1* being undercut or dovetailed to receive the dovetail bases of a series of teeth, *2 2*, kept apart by blanks or filling-pieces also set in the dovetail grooves, and each range of teeth is held in its bar by a screw or pin at the end. This picking-cylinder *d* pulls out gently, loosens, and opens the locks of wool as they pass through and are detained by the teeth of the feeding-rollers *b* and *c*, and the picking-cylinder *d* may be formed with slats or inclosing screen-wires between the bars *1 1* to let a current of air pass through, but not to let the fiber pass in, the air and centrifugal motion tending to lift the fiber off the teeth *2*. Below this picking-cylinder *d* is a screen, *e*, that prevents locks of wool that may be carried around with the teeth falling away, and a screen, *e'*, is introduced between the cylinder *d* and a suction air-trunk, *m*, so that dust will be drawn away from the space in which the cylinder *d* revolves.

The fiber is brought up to a pair of steel-ring cylinders, *f* and *g*. The second one *f*, should be closer to the teeth *2 2* than the cylinder *g*, so that the locks of wool are opened, split, and separated by the cylinders *f* and *g* and removed from the teeth *2*, the operation being so gentle (at the same time rapid) that the wool or fiber is thoroughly and quickly opened, but not injured; and to prevent injury to the wool I smooth the teeth *2*, and also the teeth of the feed-rollers *b c*, previous to the introduction of said teeth. This can be easily accomplished by any suitable means, the teeth being separate.

The burrs are knocked off by the strippers *h* and *i*, those from *h* passing into the receptacle *k*, while those from *i* fall upon the cylinder *d*, and are thrown off through the grating *e* into a receptacle below.

The fiber is taken off the cylinders *f* and *g* by the brush-blower *l* and thrown upon the condensing-cylinders *m'*, a guard, *4*, being in-

troduced to prevent the fiber from the cylinder *g* coming in contact with the stripper *i*.

The cylinders *m'* are upon vertical shafts *n*, and driven by the worm *p* and pinions *q*, and the fiber as thrown off by the blower *l* is deposited upon the perforated surfaces of these cylinders *m'* and delivered from between them in the form of a sliver or bat, and the air blowing through the wool or other fiber again conveys away any dust.

I make use of the delivery-rollers *r*, driven by suitable gearing *s*, to compress the fiber into a sliver or bat as it passes from the cylinders *m*, and to these rollers *r*, I apply oilers *t t*, formed as cans, that set against the sides of the rollers, and are sustained upon bars *u v*, and may be raised or lowered thereon to the desired height. The surfaces of the oilers *t t* next the rollers *r* are perforated with any desired number of holes, so that a constant supply of oil is applied to the surfaces of said rollers, and they oil the fiber passing between them.

The gradual opening of the wool is effected without cutting or injuring the fiber, and the dust and dirt are taken away through the trunk *m* as soon as liberated, thereby preventing such foreign substances injuring the fiber or the machinery in the subsequent operations, and the air drawing inward keeps the bearings and ends of the cylinders free from dirt and fiber (which sometimes cause friction and ignition) and the dust is not blown around the picker-room, as has been usual.

The air that passes off through the grating and trunk *m* by the exhaust-blower travels in the same direction as the picker-cylinder *d*; hence all dust and foreign substances are thrown off with the air, and the picker kept much more free from dust and dirt than is the case in those machines where the blast of air is drawn away in the opposite direction to the motion of the picker-cylinder and fiber, because said blast has to overcome the momentum of the foreign substances, while in my present invention the exhaust-blast only accelerates the momentum and centrifugal action, and the particles of foreign matter knocked from the fiber by the strippers *h* and *i* fall into the same current of air and are conveyed away from the machine.

This improvement leaves the fiber in better condition than heretofore, discharges the wool or other material in a compact form, easily handled, and in one operation effects what has usually required two or three operations attended with considerable loss of wool from the fibers being cut and broken in the picking.

The various cylinders and rollers are to be driven in the direction indicated by the arrows and at the proper speed.

I have not represented all the pulleys, gears, or wheels employed for rotating said parts, as they may be of any desired character, and the frame, movable and fixed casings, and supports or boxes for the shafts may be constructed as required.

What I claim, and desire to secure by Letters Patent, is—

1. Constructing the toothed rollers *b* and *c* with separate teeth set into grooves and secured as described.

2. The picker-cylinder formed of a series of longitudinally-grooved bars containing separate teeth and intermediate filling-pieces, substantially as specified.

3. The cylinders *d*, *f*, and *g*, in combination with the strippers *h* and *i*, substantially as and for the purposes specified.

4. The brush-blower *l* and condensing-cylinders *m'*, in combination with the picker-cylinder *d* and cylinder *f* or *g*, substantially as set forth.

5. The rollers *r r*, in combination with the condensing-cylinders *m' m'* and oilers *t t*, substantially as set forth.

6. In a picker for wool and other fiber, arranging the stripper and toothed cylinder over the picker-cylinder, so that dust and foreign substances shall fall into the space in which the picker-cylinder revolves, and be thrown out by the centrifugal action of said cylinder, aided by a current of air, substantially as set forth.

In witness whereof I have hereunto set my signature this 6th day of March, 1866.

S. R. PARKHURST.
